UNITED STATES PATENT OFFICE

NEILL MCQUEEN, OF LUDOWICI, GEORGIA.

SPRING-CUSHION TIRE.

1,034,720.

Specification of Letters Patent.

Patented Aug. 6, 1912.

Application filed December 14, 1910. Serial No. 597,384.

To all whom it may concern:

Be it known that I, NEILL MCQUEEN, a citizen of the United States, residing at Ludowici, in the county of Liberty and State of Georgia, have invented new and useful Improvements in Spring-Cushion Tires, of which the following is a specification.

My invention consists in improvements in 10 spring cushion tires disclosed in my application, Serial No. 585,150, filed Oct. 3, 1910.

The improvements consist in structural features giving a stronger construction which may be more cheaply manufactured, 15 and which is more efficient and more durable.

The tire of my prior application referred to consists of intertwined spiral strips of spring metal. The particular geometric form of the structure is of great advantage, 20 as clearly pointed out. The intertwined spirals are preferably wound in opposite directions, and are riveted and connected together at the crossing points by peripheral strips of material so that one pair of turns 25 of spirals is used to brace the pairs adjacent to it. The great number of joints necessary, however, makes the cost of manufacture somewhat high and decreases the strength, durability and efficiency.

According to the present invention I construct a spring structure of substantially the same geometric form by cutting the elements of the structure from relatively wide sheets of material, practically the entire spring 35 structure being integral and formed of a single sheet of material. Thus the great number of joints necessary to be made when the elements are separately cut and fastened together are avoided. When assembled and 40 secured on the wheel, the action of the integral cushion structure is the same, all of the advantages of the old form being secured, and in addition the efficiency, strength and durability are much increased, while the 45 cost is decreased.

I have shown in the accompanying drawings two specific embodiments of my invention.

Referring to the drawings:—Figure 1 is a 50 central transverse section of the structure applied to a wheel. Fig. 2 is a side elevation of a portion of the structure. Fig. 3 is a sectional plan view, the section being made central of the body of the structure on line 55 3—3 of Fig. 2. Fig. 4 is a plan of the form of structure as cut from the sheet. Fig. 5 is

a similar plan of the reinforcing structure. Fig. 6 is a perspective view of a section of the structure as formed for attachment to the wheel. Fig. 7 is a view similar to Fig. 3 60 of a modified structure. Fig. 8 is a transverse section of the modified structure.

The main spring structure generally (Figs. 1 and 2) is designated 10. The auxiliary inner spring structure is designated 11. The structures 10 and 11 are secured together to a common attaching rim strip 12. The rim strip is held to the rim of the wheel by two clamping members 13 and 14 clamped to the felly 15 of the wheel by bolts 16, and 70 provided with coacting wedge shaped portions 17 and 18, one of which, 18, bears against the periphery of the felly, and the other of which, 17, engages the attaching strip 12 and forces it tightly into contact with the 75 walls of the grooves 19 in the clamping members. The grooves 19 are made of such dimensions as to accommodate the clencher edges 20 of the protecting outer envelop 21 of the tire. The main spring structure 10 80 comprises a central relatively narrow peripheral strip 22, and integrally formed pairs of diverging ribs 23, 24. The pairs of ribs are similar, and the corresponding pairs of ribs are parallel, as clearly shown in Fig. 85 4 which shows the structure as cut integrally from a sheet of material. Furthermore, the pairs branch from common points, that is, the pairs on one side branch from points on the strip opposite the pairs on the opposite 90 side. These ribs 23, 24 are turned inwardly and under each other on the under side of the strip, the angle of divergence of the ribs of the pairs being such that adjacent ribs of adjacent pairs meet or approach each other 95 beneath the peripheral connecting strip 22. These ribs are connected together by being riveted to the common attaching strip 12, which extends circumferentially around the rim of the tire. Thus it will be seen that the 100 geometric form of intertwined spirals (see Figs. 2 and 3) is approximated very closely by this integrally formed structure. The ribs 24, it will be seen, are connectedly extended in the form of a spiral in one direction, while the ribs 23 extend in a similar spiral in the opposite direction.

The reinforcing spring structure 11 is similarly formed to the main structure 10, the only substantial point of difference being that the angle of divergence of the ribs of the pairs is somewhat greater. This is 105 110

on account of the fact that the reinforcing structure is smaller and because the structure is secured to the attaching strip 12 by fastening the ends of its ribs to the strip 12 intermediate the ends of the ribs 23, 24 of the main structure. By virtue of the making of the angle of divergence of the ribs of the reinforcing structure greater than that of the ribs of the main structure, the fastening may be done in this manner, and moreover a structure of the same number of spirals is made. This adds to the efficiency of operation of the structure as well as to the ease of manufacture.

15 In Fig. 7 I have shown a modification which differs from the form just described in that instead of the ribs being riveted to the attaching strip they are secured by bending their ends over to form loops 25, these loops being threaded by circumferential strips or rods 26 which are in turn riveted to the attaching strip 12 at intervals. The ends of the ribs on one side of the structure 10 are attached to one band 26, while 25 the ends on the other side of the structure are attached to another band. As many of these bands may be used as is made necessary by the dimensions of the structure and the character of the reinforcing structure. 30 Moreover they may be placed in any desired relation to each other. The ribs of the structure 11 are secured to a centrally located band 26 similar to the outer bands, the ribs being connected alternately first 35 one from one side and then one from the other.

My invention is capable also of other embodiments and these embodiments may be given it by those skilled in the art without 40 in any way departing from the generic spirit of my invention. I therefore desire to cover in the annexed claims all such modifications.

I claim:

45 1. A spring cushion structure for vehicle tires comprising a central circular strip of

material, and pairs of integrally formed diverging ribs on opposite sides of said central strip, said ribs being curved toward each other, and means securing the 50 ends of the opposite ribs together.

2. A spring cushion structure for vehicle tires comprising a central circular strip of material, ribs integrally formed with said strip and diverging in pairs from common 55 points on opposite sides of said central strip, said ribs being curved toward each other, and means securing the ends of the opposite ribs together.

3. A spring cushion structure for vehicle 60 tires comprising a central circular strip having pairs of integrally formed diverging spring ribs on opposite sides, said ribs being curved inwardly and toward each other on one side of said central strip, means 65 securing the ends of the opposite ribs together, and a similarly formed inner reinforcing spring structure, the ribs of which are secured to the aforesaid means securing the ribs together, intermediate the ribs of 70 the main structure.

4. A spring cushion structure for vehicle tires comprising a central circular strip having pairs of integrally formed diverging spring ribs on opposite sides, said ribs being curved inwardly and toward each other at one side of said central strip, means securing the ends of the opposite ribs together, and a similarly formed inner reinforcing spring structure, the ribs of which 75 have a relatively greater angle of divergence between them and being secured to aforesaid means securing the ribs together intermediate the ribs of the main structure.

In testimony whereof I have hereunto set 80 my hand in presence of two subscribing witnesses.

NEILL McQUEEN.
